UNITED STATES PATENT OFFICE.

JAMES W. BONTA, OF PHILADELPHIA, PENNSYLVANIA, ASSIGNOR TO THE AMERICAN NATIONAL TELEPHONE COMPANY, OF NEW YORK.

TELEPHONE-TRANSMITTER.

SPECIFICATION forming part of Letters Patent No. 365,781, dated July 5, 1887.

Application filed October 21, 1886. Serial No. 216,709. (No model.)

To all whom it may concern:

Be it known that I, JAMES W. BONTA, a citizen of the United States, residing at Philadelphia, in the county of Philadelphia and State of Pennsylvania, have invented certain new and useful Improvements in Telephonic Transmitters, of which the following is a specification.

My invention has relation to telephonic transmitters of the form having a series of 10 contacting electrodes and separate batteries and inductoriums for each pair or group of contacting electrodes, the secondaries of all the inductoriums being included in a common line-circuit, whereby the action of the different or 15 separate primaries simultaneously induce currents in the secondary of the separate inductoriums to produce a single working-current equal to the sum of the potentials of the separately-induced currents.

20 Heretofore in this form of instrument each group or pair of contacting electrodes is provided with separate adjusting devices for varying the initial contact-pressure of the same. I have found that when each group or pair of 25 contacting electrodes is separately adjusted it is impossible to give to each group or pair the same contact-pressure, and the contact-pressure of one or more of them varies from that of the others, and if great care be not exercised in 30 making the adjustments the contact-pressure of all of them will be different. This variation in contact-pressure of the groups or pairs of contacting electrodes subjects different parts of the diaphragm to different degrees of pressure when in action, so that its action is not 35 uniform throughout its area and unequal impulses are produced in the separate inductoriums.

My invention has for its object to avoid the 40 above-described results, and this I accomplish by simultaneously adjusting the contact-pressure of all the groups or pairs of electrodes to give to each pair or group the same or an equal contact-pressure, whereby the action of 45 the diaphragm produces equal current-impulses in all the inductoriums for augmenting or intensifying the secondary or working current for the line.

My invention accordingly consists of a tele- 50 phonie transmitter having a number of sepa-

rate contacting electrodes, each pair or group of contacting electrodes having a separate battery-circuit, including the primary of separate inductoriums, the secondary of which is a part of or included in the line, and adjusting mechanism for simultaneously varying the contact-pressure of all the pairs or groups of the contacting electrodes equally, as hereinafter more fully described and claimed.

55 In the drawings I have shown my invention applied to the form of telephonic transmitter shown and described in United States Patent granted to me on the 5th day of January, 1885, and numbered 333,816, or that form wherein a rolling or loose electrode on an inclined table 65 has contact with the diaphragm or an electrode thereon, and in which—

Figure 1 is a vertical section of the transmitter. Fig. 2 is a rear view of electrodes, inclined tables or blocks, adjusting mechanism, 70 diaphragm-inductoriums, and circuit-connections; and Fig. 3 is a vertical section showing modification of construction of parts of the transmitter.

75 While I have shown the above-described form of transmitter, I do not confine myself thereto, as my improvements are applicable to any form of transmitter having multiple contacts.

A represents a transmitter-casing having removable cap *a*, provided with mouth-piece *a'* and diaphragm *B*, with or without electrode *b*.

80 C represents the inclined table, of carbon or metal, grooved or otherwise, as desired. Upon the table *C* is a rolling or loose electrode, *D*. 85 Two or more of the electrodes *b* are secured to the diaphragm, and a corresponding number of electrodes *D* and tables *C* are provided for electrodes *b*, to obtain multiple contacts or pairs of electrodes, each of which is in circuit 90 with the primary 1 of a separate inductorium, *I*, each of which primaries includes a separate battery, 2, and the secondaries 3 of all the inductoriums are in circuit with a single or common line, 4, as more plainly shown in Fig. 2, 95 so that each pair of electrodes, when operated simultaneously, varies or impulses a separate battery-current and these separate battery-current impulses simultaneously induce separate currents in the secondaries of separate induct- 100

toriums to produce one working or line current of a potential equal to the sum of all the separately-induced currents. Each pair of electrodes, as well as each block or plate C therefor, is insulated from all the others, and the circuit-connections between the primaries and electrodes may be provided for as shown or as desired.

In Figs. 1 and 2 I have shown six pairs of electrodes arranged in two rows or series, one above the other.

The platforms G for the blocks are pivoted to casing-standards g, and have an adjusting-rod, h, suitably made and held in its adjusted position by a set-screw, h'. By moving bar h up or down, all the blocks are simultaneously adjusted as to their inclination, and the degree of contact-pressure for all the pairs of the electrodes is correspondingly varied, so that the contact-pressure for the electrodes is the same or equal throughout both series or rows of same.

In Fig. 3 only one row of three pairs of contacts or electrodes is shown; but the number 25 may be varied as desired, and the tables C or platforms G have a single adjusting screw, h'.

What I claim is—

1. A telephonic transmitter having multiple or a number of separate pairs of electrodes, 30 separate inductoriums for each pair of electrodes, separate batteries in the primaries of

the inductoriums, the secondaries of all of which connect with the line, and adjusting devices for simultaneously and equally varying the initial contact-pressure of the groups or 35 pairs of contacting electrodes, substantially as set forth.

2. A telephonic transmitter having a number of separate pairs or groups of contacting electrodes, a single adjusting device for simultaneously varying their initial contact pressure, separate inductoriums for each pair of contacts or electrodes, and a separate battery in the primary of each inductorium, the secondaries of all of which are in circuit with the line. 40

3. In combination with a diaphragm having a number of loose or rolling electrodes in contact therewith, separate circuit-connections for each electrode with the primaries of separate inductoriums, a separate battery in the 45 primary of each inductorium, the secondaries of which are in circuit with the line, and an adjusting device for simultaneously and equally varying the initial contact-pressure of the contacting electrodes, substantially as set forth.

In testimony whereof I affix my signature in presence of two witnesses.

JAMES W. BONTA.
